EXPANSIVE REAMER

John Grant, Los Angeles, Calif.

Application February 20, 1939, Serial No. 257,426

3 Claims. (Cl. 255—76)

This invention relates to expansive well reamers; and it is among the objects of the invention to produce an effective and rugged reamer of large expansive capacity; to produce such a reamer in such form and of such strength and ruggedness that it can utilize, and will withstand the forces resultant from the use of, roller cutters; and further to produce such a reamer of large expansive capacity and cutting efficiency, which is actuated by hydraulic pressure and in which the cutting action of the mud laden circulation fluid is minimized. It is also an object of the invention to produce such a tool as herein referred to in simple and rugged form. And there are many other objects and corresponding accomplishments of the invention which, together with the foregoing, will be better understood from the following preliminary discussion and specific description of illustrative forms embodying the invention.

In the past expansive well reaming tools using blade type cutters, sometimes known as wall scrapers, have been designed to have an expansive capacity relatively large as compared with the more limited expansive capacity of the expansive reaming tools which are commonly known in the trade as underreamers and commonly use cutters of the roller type. These large expansive tools have commonly used expansive cutters of the blade or scraping type. They have commonly been actuated by hydraulic pressure. But their serious limitations have been due to their inability to utilize roller cutters with their accompanying superior and dependable cutting action, to their relative weakness of design particularly with relation to the thrusts and forces which would be imposed upon them if roller cutters were used, and to their lack of simplicity and ruggedness of structure with relation to their hydraulic actuation of the cutters, and as well their tendency to have their parts cut out by the abrading action of the mud laden circulating fluid. It may be stated as one general object of the present invention to overcome these priorly encountered difficulties. Among these objects I may, without minimizing others, particularly emphasize that of providing a tool using roller cutters but having large expansion. The prior blade cutters have large expansion, but they wear so quickly that they cannot be depended upon to enlarge any substantial footage of hole in hard formation to any definitely determinable diameter. In this connection, the object of the invention is to attain the desired expansion in a tool utilizing roller

cutters, so that the enlargement of the hole to a definitely predetermined size can be relied on.

In one aspect of my present invention, it may be regarded as an improvement upon the type of hydraulic cutter actuation which is the subject-matter of copending application Ser. No. 167,389, filed October 5, 1937, by James J. Santiago. My present invention utilizes certain of the fundamental features of structure and function shown in said Santiago application, and further improves upon that prior structure by simplifying the interconnection between the hydraulically actuated plunger and the expansively movable cutters, by making a part of the plunger directly contact the cutters both for purposes of their expansive movement and for forming an abutment for the cutters when expanded. And further, as compared with the type of tool shown in said Santiago application, my present invention further improves the mounting of the cutters, particularly as to solidity and strength and ability to take the thrusts and forces which are developed upon roller cutters.

The invention in its various aspects will be best understood from the following detailed description of certain illustrative and typical forms of expansive reamer illustrated in the accompanying drawings in which

Fig. 1 is a vertical central longitudinal section of an expansive reamer illustrative of the invention;

Fig. 2 is a fragmentary elevation of the same; Fig. 3 is a section taken on line 3—3 of Fig. 1;

Fig. 3a is a cross section on line 3a—3a of Fig. 1;

Fig. 4 is an enlargement of certain portions of the sectional view of Fig. 1;

Fig. 4a is a similar view showing the parts in contracted position;

Fig. 5 is a diagrammatic perspective showing the inner end of a cutter arm;

Fig. 6 is a similar fragmentary section showing adaptation to a different type of roller cutter, the cutter in this view being shown in contracted position; and

Fig. 7 is a section showing adaptation to another type of roller cutter.

In the drawings the tool is shown as having a hollow body 10 adapted at its upper end for attachment to a sub, or drill stem or the like, indicated at 11. In its upper part this body 10 has a main plunger bore 12 in which a plunger head reciprocates, indicated generally by the numeral 13. Immediately below the plunger

bore 12 there extends a somewhat smaller plunger guide bore 14, in which the depending plunger 15 reciprocates. The lower end of the guide bore 14 opens into a larger body bore 16 which extends to a point near the lower end of the tool where the body carries the usual bit 17. In the drawings this bit is shown as being integral with the body, although it need not be so.

It is preferred that a tool of this character have three cutters, and accordingly the body is provided with three cutter-receiving slots 20, of which the lower portions 21 are of sufficient width to take the roller cutters hereinafter described, and the upper portions 22 are of narrower width and adapted snugly to take the thicknesses of the swinging cutter arms 23. As shown in the present illustrative design, the upper ends of the lower and wider portions of slots 21 extend to the line shown at 26 in Figs. 1 and 4, this line also demarcating the lower extremity of the narrow upper slot portions 22. As shown in the cross sections of Figs. 3 and 3a, the upper narrower slot portions 22 do not cut away the entire inner surface of the body, so that portions of the cylindric surface of the bore 16 are left between adjacent slots, as indicated by the numeral 16a. The purpose and utility of these surfaces will appear later. The upper end of the lower large body bore 16 extends up to the shoulder marked 27 on Figs. 1 and 4, above the line 26 which marks the lower ends of the narrow body slots 22. The purpose of this arrangement, as will become more clear hereinafter, is to provide certain shouldering faces on the surface of the upper part of that large body bore adjacent the swinging cutter arms 23. In the design as here shown, the transverse pivots 28 for the swinging cutter arms 23 are mounted approximately at the level of the said shoulder 27. And this shoulder 27, in such position relative to the cutter pivots, also demarks the lower end of the plunger guide bore 14.

Each swinging cutter arm 23 carries at its outer end a roller cutter 30, of which the details and variations will be considered later. At the instant it is sufficient to note that the swinging arms of the present illustrative tool have been designed to take expanded positions swung outwardly to about the 60° angle shown for instance in Figs. 1 and 4, although this particular angle is not necessary, and to take contracted positions hanging vertically downwardly in the body slots 20, as shown in Fig. 4a. It is the general purpose and function of the parts now to be described to cause and allow expansive and contractive movements of the cutter arms, and to ruggedly support the cutter arms and cutters against all the forces and thrusts which are imposed upon them.

The plunger head 13 shown in Fig. 1 is substantially similar to the corresponding plunger head shown in the said Santiago application, and to it in itself I make no claim. This plunger head has a relatively large hollow interior 35, and an upper preferably conical end 36 having two or more narrow entrance slots 37 through which the circulation fluid flows downwardly and inwardly, and in restricted high velocity streams into the large plunger interior in opposed relation so that the high velocities are broken up by interimpingement of the streams. The back pressure set up by these restricted slots 37 is the pressure which tends to force the plunger head 13 downwardly. The plunger head carries a packing ring 38 engaging the wall of bore 12 to prevent leakage of fluid past the head.

The hollow plunger 15 forms a direct downward

extension of plunger head 13, and this plunger 15 plays in the plunger guide bore 14 with a sufficiently close fit to guide the plunger fairly accurately and to enable it to form an interior central and common abutment for the several cutter arms, as hereinafter described.

At the same time, the plunger 15 fits bore 14 with sufficient clearance that fluid circulation may be maintained through the clearance if desired, as hereinafter explained. In the operation of the device the plunger 15 moves between its lowermost position shown in Fig. 1 and its uppermost position shown in Fig. 4a. To prevent the plunger from rising much beyond its uppermost position, any suitable motion limiting means may be used. In the present instance I have shown a stop sleeve 40 depending from the sub 11 and adapted to form a stop to limit the upward movement of plunger head 13 to a position that corresponds to, or a little above, the upper position of plunger 15 shown in Fig. 4a. To limit downward movement of the plunger and prevent it from moving on down and locking the cutter arms in expanded positions, any suitable stop means may be used. For instance in Fig. 1 stop lugs 41 are shown on the plunger, engaging the shoulder 42 at the lower end of bore 12.

The interior chamber 35 of plunger head 13 is continued on downwardly through plunger 15 by the plunger bore 45. The lower part of this bore is diminished in size, as at 46 and loosely takes the upper end of the circulation pipe 47 which is mounted at its lower end in bore 48 in the lower end of the body. From bore 48 circulation ducts, such as 49 and 50, lead off to deliver circulation to bit 17 and outwardly and upwardly under the cutters 30. The use of an interior central circulation pipe, as here described, obviates the necessity of carrying circulation to the lower part of the body by passages leading down through the outer parts of the body, as is usually done in tools of the kind described here. Such circulation passages materially weaken the body at its slotted portion. The central pipe obviates all such weakening.

Bore 46 of the plunger 15 is recessed at 46a to provide an annular channel in which packing may be inserted if it is desired not to have downward circulation through the clearance in bore 46 surrounding pipe 47. The stop sleeve 40 prevents plunger 15 from rising high enough to move out of engagement with either the circulation pipe 47 or the body bore 14. When the tool is being run into a well, the upward flow of fluid through the tool is otherwise liable to move the plunger up out of proper engagement.

Before explaining the details of the cutter mountings and abutments I will first explain the modes of circulation that may be had. As shown in the drawings the lower part of the plunger head 13 has large openings 55 in its wall, so that circulation may pass from the interior chamber 35 of the head into the bore 12 below packing 38. If these openings 55 are used, then a part of the circulation passes down through the annular clearance around plunger 15 in bore 14 and is delivered at the lower end of bore 14 directly over the inner ends of the cutter arms 23, and thus serves as circulation to the immediate vicinity of, or above, the cutters. However I note particularly that the openings 55 may be dispensed with and the wall of the chamber 35 made solid, in which case there will

be no circulation around the outside of the plunger.

As is seen in the drawings, the upper end of circulation pipe 47 communicates directly with the plunger bore 45 and head chamber 35, so that circulation from the chamber interior takes place through that pipe to the circulation ducts at the lower part of the body. Furthermore the annular clearance around pipe 47 in plunger bore 46 also communicates directly with bore 45 and head chamber 35, so that circulation may be maintained through that clearance if desired. This circulation, if used, discharges at the lower end of plunger 15 near, or directly under, the inner ends of the cutter arms 23, and thus discharges in the direct vicinity of the cutters.

Like the circulation around the outside of plunger 15, that around the outside of pipe 47 may be dispensed with if desired, by inserting packing in the channel 46a. On the other hand, if circulation is maintained around the outside of the pipe, it may either be comparatively small or large in quantity, as the clearance is made small or large. Either one or both, or neither, of the above circulations may be used; and if used they may be made to be of any desired relative volumes by constricting or enlarging the clearances.

In any case, regardless of which circulation passages are used, it will be seen that all of them are fed from the large interior chamber 35 of the plunger head, and that that chamber can only receive circulation through the restricted ports 37. These restricted ports are preferably so dimensioned that their total area is less than the smallest total flow area beyond the head chamber 35. For instance, if only the circulation pipe 47 is used for circulation, then the total area of ports 37 is preferably less than that of pipe 47, so that the highest velocities are set up at the ports 37 and substantial actuating pressure is applied to the plunger head, and also so that substantially all the cutting and wear due to high velocity streams is localized at ports 37. Once the high velocity streams enter the large chamber 35 in the plunger head, all high velocity flow ceases. From that chamber the flow, by whatever routes it travels, is relatively slow and quiet.

Each cutter arm 23 has in its inner end a recess 60 whose back face 61 is cylindric and of a curvature to fit the cylindric face of plunger 15. This recess is so aligned in the cutter arm that its cylindric wall is vertical when the cutter arm is in expanded position, as shown in Figs. 1 and 4. The bottom 62 of recess 60 is located and shaped so as to fit the conical end surface 63 of the plunger. In the expanded position of the arm the recess bottom 62 is below the swinging center of the arm on pivot pin 28, and the end portion of the plunger is somewhat relieved at 64 above conical surface 63 so that the conical surface 63 may keep in contact with recess bottom 62 as the arm swings between the expanded position of Fig. 4 and the contracted position of Fig. 4a. In the contracted position, shown in Fig. 4a, the conical seating end of the plunger may still rest on the recess bottom 62, although not flatly. When the plunger is forced downwardly by the hydraulic action, downward pressure of the plunger end on the recess surfaces 62 forces the cutter arms to the expanded positions of Figs. 1 and 4. In that position the lower end of the plunger seats on the recess bottoms 75

62, and the walls 61 of the recesses bear closely against the cylindric surface of the plunger. By this arrangement all the cutter arms are given mutually a solid internal backing against the central plunger so that inward pressures on the arms are sustained. In case the lower walls of the recesses 60, at the lower wall surfaces 62, should break off or wear away, the previously explained stops 41 on the plunger prevent the plunger from moving on down below its proper lowermost position and locking the cutter arms so that they could not be swung downward for retraction. Retraction is effected by pulling the tool up into the well casing, the arms contacting the casing shoe and being swung down and in. When the arms are thus swung down they raise the plunger to its upper position.

In the expanded positions of the arms, their upper surfaces, at points outside the pivot centers 28, bear upwardly against abutment surfaces 65 which are located on the body at the upper ends of the body slots. In the particular design as here shown, where the upper surfaces of the arms are at an angle, the abutment faces 65 are likewise at that angle, so that flat seating is attained. The function of these abutment surfaces is to form a stop, located at one side of the pivot 28, to limit upward swinging of the cutter arm.

The stop lugs 66, with their shouldering faces 67, form other abutments at the opposite sides of the pivots 28 to limit upward swinging of the cutter arms. These stops are formed on the opposite faces of the arms at their inner ends, in such positions that their faces 67 bear outwardly against the faces 16a of the bore 16 when the cutter arms are expanded. See Figs. 3 and 4. These rotational stops being located opposite to the rotational stops 65, they take all or substantially all the thrusts which are generated by forces tending to rotate the arms upwardly, and thus take the resultant shearing stresses off the pivot pin 28. The major forces to which the cutters and cutter arms are subjected are upward forces, inward forces and circumferential forces. The upward forces acting on the outer ends of the cutter arms are here taken care of by the stops above described and also by the recess surfaces 61 bearing against the central plunger. These bearing faces and stops take off the pivot pins shearing stresses that would otherwise be placed upon them. The inward forces that would also otherwise have to be carried by the pivot pins are taken by the inward bearings of the arm faces 61 on the central plunger. Circumferential forces acting on the outer ends of the cutter arms are taken care of by the lateral bearing of the side faces of the arms against the side walls of the upper narrow portions 22 of the body slots 20. The cutter arms are thus solidly supported at their inner ends against all thrusts, and accordingly they can be made long enough to carry roller cutters at a considerable expansion diameter, and still carry all the thrusts to which the roller cutters located at such a cutting diameter are subjected in heavy service.

Various forms of roller cutters may be carried on the outer ends of the cutter arms, the particular form being dependent upon the service required. Figs. 1 to 4 show roller cutters 30 arranged on axes longitudinal of the arms. As shown in Fig. 1, the outer end of the arm may be shaped to form a tapering pin 70, and the cylindric cutter body 71 has a corresponding bore. The outer end 72 of the cutter may be conical, and provided with cutting teeth, as is the cylin-

dric surface. The outer end of the cutter bears back against an end-thrust bearing ball 73. Near the inner end, the cutter may have bearing on balls 74 which, running in races 75 and 76 in the cutter and the bearing pin 71, also serve to hold the cutter endwise on the pin.

In Fig. 6, a roller cutter 30a is shown mounted on an axis pin 80 whose axis is at an angle to the length of the arm 23a and at right angles to the axis of pivot pin 28. Axis pin 80 is held in arms 81 at the outer end of the cutter arm 23a. And thrust washers 82 are provided at the ends of the roller cutter; the cutter runs on roller bearings 83, and the pin 80 is secured solidly in place as by being welded as at 84. This figure also shows a cutter arm that is not swung out to such a wide angle as shown in the other figures. This is accomplished by placing the roller cutter axis at such an angle as illustrated relative to the length of the arm.

In Fig. 7 another type of roller cutter is shown, a crown cutter 30b. Here again the cutter rotates on an axis longitudinal of the cutter arm 23b. The outer end face 85 of this cutter is frusto-conical and has teeth 86. The outer part of the cutter has a central bore 87, and the inner part of the cutter a large bore 88. This inner large bore takes a ball race ring 89 and ball bearings 90 which take both radial and end thrust. The race ring is held non-rotative by pins 91. Between bores 88 and 87 the cutter has an internal flange 92 which surrounds a reduced portion 93 of an axial boss 94 integral with arm 23b. A retention screw 95 has its head 96 overlying the flange 92, and the screw is locked against loosening by the lock pin 97.

These and various other forms of roller cutters may be utilized, in fact any roller cutter form that can effectively be mounted on the outer end of such arms as I describe. My invention is not limited to any particular form of cutter, being characterized by its provision of rugged and solidly mounted cutter arms capable of giving large expansion regardless of the type of cutter used, but capable of utilizing roller cutters.

I claim:

1. In an expansive reamer, an elongate body having in its upper portion a plunger receiving bore, a plunger with an upper plunger head reciprocable vertically in said bore, said plunger having a longitudinal bore open at its lower end and the plunger head being hollow and in communication with the plunger bore, a restricted fluid entry port in the upper end of the plunger head, a packing surrounding the plunger head below the restricted port, the plunger below said packing fitting the body bore with clearance for passage of circulation, the plunger head having

an opening through its wall below the packing, a circulation pipe mounted in the lower part of the body and entering the lower end of the plunger bore to receive fluid therefrom, the body having cutter arm receiving slots immediately below the plunger bore, and cutter arms pivoted in said slots and adapted to take the lower end of the plunger between them.

2. In an expansive reamer, an elongate tubular body having longitudinally extending radial cutter arm receiving slots through its walls, swinging cutter arms in said slots mounted to swing on pivots which extend transversely of the body and across the slots, said arms adapted to swing from positions longitudinal of the slots to positions extending outwardly from the body, stop means on the body adapted to engage the arms at a point radially removed from the arm pivots and adapted to limit outward swinging of the arms, and other stop means on the arms at the opposite side of their pivots and adapted to engage the body to limit outward swinging of the arms, the pivoted ends of the arms having plunger receiving recesses which recesses have side walls lying in a cylindric formation when the arms are extended and which recesses also have end walls, and means in the body for swinging the arms outwardly, said means including a cylindric plunger movable longitudinally of the body to engage its end with the said recess end walls and adapted to be received in the several recesses to form a central abutment between the arms.

3. In an expansive reamer, an elongate tubular body having longitudinally extending radial cutter arm receiving slots through its walls, said slots terminating at their upper ends at downwardly facing wall shoulders, swinging cutter arms in said slots mounted at their upper ends to swing on pivots which extend transversely of the body and across the slots near their upper ends, the arms adapted normally to hang downwardly from the pivots and to swing upwardly and outwardly from the body, each arm having a stop surface at its outer side near its top adapted to engage a wall shoulder, each arm having a projecting stop shoulder adjacent its inner side near its top and adapted to engage the inner surface of the tubular body, the upper pivoted ends of the arms having plunger receiving recesses which have side walls that lie substantially vertically when the arms are swung outwardly and which also have bottom walls, and a downwardly movable plunger in the body adapted to engage its lower end with the several recess bottom walls and adapted to be received in the several recesses to form a central abutment between pivoted ends of the cutters.

JOHN GRANT.
